UNITED STATES PATENT OFFICE

COLIN OLIVER DEACON, OF WELGEDACHT, TRANSVAAL, SOUTH AFRICA

MEANS FOR DERAILING TUBS, TRUCKS, AND THE LIKE

Original application filed March 20, 1929, Serial No. 348,581. Patent No. 1,749,803, dated March 11, 1930, and in Union of South Africa October 5, 1928. Divided and this application filed September 19, 1929, Serial No. 393,803.

This invention relates to means designed for derailing tubs, trucks, and other railway vehicles, or diverting them off a permanent way or track, in the event of their running away down or along the track, or attaining an excessive or uncontrollable speed; and the present application is a division of application Serial No. 348,581, filed March 20, 1929, Patent No. 1,749,803, March 11, 1930.

10 The invention is applicable for use on railway tracks of any description, for derailing, diverting, or throwing off the track, tubs, trucks, or other railway vehicles or the like, whether loaded or empty, which 15 have acquired a predetermined excessive or uncontrollable speed on the permanent way or track.

20 The means according to this invention constitutes a simple and efficient device for the purpose specified which, when the vehicles are running at or below the normal or a predetermined maximum speed, will allow them to remain on the track, and will operate, only on such speed being exceeded, to 25 derail the vehicle.

According to this invention the derailing device consists of a definite "setting" in or shaping of the track, so as to impart to a portion or portions thereof a transverse or 30 lateral kink or bend, with an upward grade or incline (relative to the level of the rails of the track) for a portion of the set or bend, in the direction of the travel of the vehicle along the permanent way.

The transverse set, or lateral kink or bend, may be provided by parts or castings placed between the adjacent ends of adjacent rails of the track, and shaped to provide the set or bend and the upward grade or incline; or 40 the set or bend may be formed in the rails of the track themselves and the upward grade or incline be provided by pieces or castings shaped to correspond to the kink or bend in the rails and fixed on the top thereof at the 45 set or bend.

The transverse set, or lateral kink or bend, causes the vehicle to be deflected or diverted laterally from the normal direction of travel and to be returned to said normal direction 50 when the vehicle is running at normal or safe

speeds. The set or bend, combined with the upward grade or incline, causes the vehicle to be derailed when it acquires an excessive or uncontrollable speed; whereas, at normal or safe speeds, the vehicle passes over the device 55 without being derailed. It will be understood from the foregoing that the construction of the device is such that the upper surface of the deflecting device rises above the normal plane of the rails of the track from 60 both ends of the device.

The invention will be more fully explained with the aid of the accompanying drawings, wherein I illustrate two forms thereof. In 65 the drawings,

Figs. 1 and 2 are plan view and side elevation, respectively, of a portion of the permanent way or track, showing one form of the invention, and

Figs. 3 and 4 are similar views illustrating 70 the other form of the invention.

In the form of the invention depicted in Figs. 1 and 2, the transverse set, or lateral kink or bend, is formed in castings or parts made separate from the rails of the track and interposed between the adjacent ends of adjacent rails 1, 1^a, and 2, 2^a, of the track. Although the track is shown as a horizontal track, it is to be understood that it may be either upwardly or downwardly inclined and the device still operate to derail the vehicle under the conditions hereinbefore mentioned. The castings or parts are so arranged relative to each other in the track that the sets or bends therein are symmetrical and incline laterally in the direction of the same side of the track, so that the gauge is maintained for the full length of the derailing device.

3, 4, represent two of the sleepers of the permanent way or track, on which sleepers the end portions of the castings or parts rest and are secured. Each of the castings or parts, as shown more particularly in Fig. 1, is shaped or bent laterally or transversely 95 of the track from the point 5 to the point 6, and then in the opposite direction to the point 7.

8 indicates the top or highest points of the upwardly inclined portions 9 of the de- 100

vice. From the points 8 to the points 6 the portions 10 are bent downwardly, while the portions 11, from the points 6 to the points 7 are bent downwardly at a lesser angle to the horizontal than the portions 10—see Fig. 2.

The parts or castings are shown constructed with flanges 12, and they are connected at their ends to their respective rails 1, 1^a, and 2, 2^a, by means of the fish plates 13.

As will be apparent from a consideration of this embodiment of the invention, the set or shaping of the castings or parts is such that, in the event of a vehicle passing on to the derailing device at an excessive speed, it is diverted or deflected transversely, and upwardly relative to the plane of the track; by the portions 9, and, due to its momentum, tends to continue in the same direction, as indicated by the dotted lines *a*. The action of gravity compels the wheels of the vehicle to travel or move in a curved path or trajectory, as indicated by the dotted curve *b* in Fig. 2. This causes the wheels to leave or jump clear of the track, thereby resulting in the derailing of the vehicle.

In the other form of the invention shown in Figs. 3 and 4, the rails 1, 2, of the track are constructed with a transverse set, or lateral bend, in the plane of the track; and appropriately shaped pieces or members 14, providing the inclined surfaces 9 and 11, and constructed with the set or bend corresponding to the set or bend in the rails, are fixed, by means of screws 15, on the tops of the rails 1, 2. This construction operates to derail the vehicle in the manner previously described in connection with Figs. 1 and 2.

In both of the forms of the invention shown in the drawings the device is supported by sleepers, but it will be apparent that it may be otherwise supported, as for example by arranging it upon a metal plate or plates, or on a cast base; or it may be cast or otherwise constructed integral with a base or base portion.

It follows from the foregoing description that the device in both forms as described and illustrated, is entirely self-contained, and that there are no moving parts liable to get out of order, as in existing arrangements employed for the purpose. Further, that my improved device is not, like the existing arrangements, difficult to install. It does not call for special attention, and does not require the amount of space which is necessary for the working parts of existing devices. My device, being of simple construction, is inexpensive to produce and cannot get out of order. It is light in weight and inexpensive to install.

What I claim as my invention and desire to protect by Letters Patent is:—

1. A railway permanent way or track, a portion of which is constructed with a trans-

verse or lateral set or bend and an incline co-operating with said set or bend, whereby the vehicles are derailed when they acquire an excessive or uncontrollable speed, said set or bend and incline being provided in parts which form portion of the permanent way or track and are fixed to the rails thereof, as set forth. 70

2. A railway permanent way or track, a portion of which is constructed with a transverse or lateral set or bend and an incline co-operating with said set or bend, whereby the vehicles are derailed when they acquire an excessive or uncontrollable speed, said set or bend and incline being provided in parts which are fixed to the rails and symmetricaly arranged in and form portion of the permanent way or track, as set forth. 75

3. A railway permanent way or track, a portion of which is constructed with a transverse or lateral set or bend and an incline co-operating with said set or bend, whereby the vehicles are derailed when they acquire an excessive or uncontrollable speed, said set or bend and incline being provided in members which are arranged and secured between adjacent ends of adjacent rails at both sides of the permanent way or track, as set forth. 80

4. A railway permanent way or track, a portion of which is constructed with a transverse or lateral set or bend, and members providing an incline and fixed upon and co-operating with the set or bend in the permanent way or track, whereby the vehicles are derailed when they acquire an excessive or uncontrollable speed, as set forth. 90

5. A railway permanent way or track, a portion of which is constructed with a transverse or lateral set or bend, and members having a corresponding set or bend and providing an incline, and fixed upon the set or bend in the permanent way or track, said set or bend and incline co-operating to derail the vehicles when they acquire an excessive or uncontrollable speed, as set forth. 100

In testimony whereof I have signed my name to this specification.

COLIN OLIVER DEACON.
